J. L. HARRIS

CARD GAME APPARATUS

Filed Dec. 24, 1923

John L. Harris, INVENTOR.

BY

BY
Geo. P. Kimmel.

ATTORNEY.

UNITED STATES PATENT OFFICE.

JOHN L. HARRIS, OF WATER VALLEY, MISSISSIPPI.

CARD-GAME APPARATUS.

Application filed December 24, 1923. Serial No. 682,473.

To all whom it may concern:

Be it known that I, JOHN L. HARRIS, a citizen of the United States, residing at Water Valley, in the county of Yalobusha 5 and State of Mississippi, have invented certain new and useful Improvements in Card-Game Apparatus, of which the following is a specification.

This invention relates to a card game apparatus, and has for its object to provide, in a manner as hereinafter set forth, an apparatus of such class provided with means for playing card games which are not only novel, but also possess special features of interest and afford considerable amusement 15 during the progress of the games, as well as being highly instructive in the use of coins and practice in addition and subtraction of figures.

With the foregoing and other objects in view, the invention consists of the novel construction of card game apparatus as hereinafter more specifically described and illustrated in the accompanying drawings, 25 wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figures 1 to 14, both inclusive, illustrate in front elevation one of the sets of cards of 35 the card game apparatus, in accordance with this invention.

Figure 15 is a front elevation of one of the cards of another of the sets of the card game apparatus in accordance with this 40 invention.

Figure 16 is a like view of one of the cards of another of the sets of cards of the card game apparatus in accordance with this invention.

Figure 17 is a front elevation of one of the cards of the other of the sets of cards of the game apparatus, in accordance with this 45 invention.

Figure 18 is a rear elevation of any one of the cards of any one of the sets of the card game apparatus.

The card game apparatus in accordance with this invention, comprises a pack of fifty-six cards divided into four sets and 55 each set consisting of fourteen cards. The

cards of each set are constructed alike, with this exception, that the sets of cards are differently colored.

One set of cards is indicated at 1, another at 2, another at 3 and the other set at 4. 60

The colors of the sets are shown by way of example as green, red, black and yellow, but it is to be understood that the sets can be differently colored if desired. As shown, the front faces of the set of cards 1, are 65 green, the cards 2 red, the cards 3 black and the cards 4 yellow.

The backs of the cards of all of the sets are similar in design, or similar in color, and as shown in Figure 18 the back of the card 70 is indicated at 5 and provided with conventional means, as at 6, to indicate a coin and with such means of circular contour. Extending diametrically of the said means 6, are two similar words, such as "Coins" as 75 at 7, and the two words are disposed at right angles with respect to each other. It is to be understood, however, that the back of each of the cards can be of any suitable design but with the back of each card provided 80 with a similar design or color.

The front faces of the cards of each set, other than the different color for each set, are constructed alike, and it is to be understood that the description of the cards of the 85 set 1 will apply to the cards of the other sets 2, 3 and 4.

The cards of each set are indicated at 8, 9, 10, 11, 12, 13, 14, 15, 16, 17, 18, 19, 20 and 21. 90

The card 8 of each set is provided centrally with conventional means to constitute the representation of a dollar, as indicated at 22, and the said means is in the design of a disk in perspective having the designation 95 "One dollar" thereon. At one upper corner of the front face of the card 8 an indicator, as at 23, is arranged and which is shown as the conventional dollar mark, and at one lower corner of the outer face of the card 8 100 an indicator, as at 24 is arranged and which is shown as a conventional dollar mark. The indications 23, 24 set forth the value of the card from a financial or currency standpoint. 105

The outer face of the card 8 is furthermore provided with a rectangular Figure 25 which surrounds the dollar indication 22.

Each of the cards 9, 10, 11, 12 and 13 of each set has its outer face provided with a 110

rectangular figure 26, which is similar to the figure 25.

Each of the cards 9 of each set has arranged on its face and within the rectangular Figure 26 conventional means, as at 27, 28, to indicate respectively "Half dollar" and "Quarter dollar." The conventional indication 27 is arranged above the indication 28, and the indication 27 as well as the indication 28 is in the design of a circular disk shown in perspective. The disk of the indicating means 27 is provided with the term "Half dollar" and the disk of the indication 28 is provided with the term "Quarter dollar."

The card 9 of each of the sets has its outer face at one upper corner thereof provided with conventional means, as at 29, to indicate 75¢ and the outer face of said card, at 20 one lower corner thereof is provided with conventional means, as at 30, to indicate 75¢. The means 29 and 30 constitute indications to set forth the value of the card 9 from a financial or fractional currency standpoint.

25 The card 10 of each of the sets of cards, has arranged within the rectangular figure 26, conventional means, as at 31, to indicate "Half dollar," and said means is in the design of a disk shown in perspective and provided with the term "Half dollar." The outer face of the card 10, at one upper corner and at one lower corner thereof, is provided with conventional means, as at 32, 33, such as 50¢ to indicate the value of the 35 card 10 from a financial or fractional currency standpoint.

The card 11 of each of the sets of cards has arranged within the rectangular figure 26, conventional means, as at 33, to indicate 40 "Quarter dollar" and said means consists of the design of a disk in perspective provided with the term "Quarter dollar." Arranged within the rectangular figure 26, near each end of the card 11, is the term "Flip" as 45 indicated at 34, 35. The outer face of the card 11, at one upper corner and at one lower corner is provided with conventional means as at 36, 37, to indicate 25¢, and the said means indicates the value of the card 50 11 from a financial or fractional currency standpoint.

The card 12 of each of the sets, has arranged within the rectangular Figure 26, conventional means, as at 38, to indicate 55 "One dime," and said means consists of a design of a disk in perspective provided with the term "One dime." The outer face of the card 12, near each end thereof is provided with the term "Flop," as at 39, 40. 60 The outer face of the card 12, at one upper corner and at one lower corner, is provided with conventional means, as at 41, 42, to indicate 10¢, and said means 41, 42, indicates the value of the card 12 from a financial or fractional currency standpoint.

The card 13 of each set, has arranged within the rectangular figure 26, conventional means, as at 43, to indicate "Five cents" and said means is in the design of a disk shown in perspective, provided with 70 the term "Five cents." The outer face of the card 13, at one upper and at one lower corner thereof is provided with conventional means, as at 44, 45, to indicate 5¢. Said means 44, 45 indicate the value of the 75 card 13 from a financial or fractional currency standpoint.

The card 14 of each set has its outer face provided with conventional means to provide two spaced rows of superposed indications to constitute representations of "One cent," and each of the indications is in the design of a disk in perspective, provided with the term "One cent." The indications of one row are designated 46, 47, 48 and 49, 80 and the indications of the other row are designated 50, 51, 52 and 53, and arranged between the rows is conventional means, as at 54, to constitute the representation of "One cent" and which is in the design of a disk in perspective, provided with the term "One cent." Nine one cent indications are provided to indicate that the card 14 is of a value of nine cents. The card 14 has its outer face at one upper corner and one lower 95 corner provided with an indication 9¢, as at 55, 56.

The card 15 of each set has its outer face provided with conventional means to provide a pair of outer and an inner row of 100 superposed indications, each constituting the representation of "One cent" and is in the form of a disk shown in perspective, provided with the term "One cent." The indications of one outer row are indicated at 57, 58 and 59, the other outer row at 60, 61 and 62, and the inner row at 63, 64. Eight indications are provided on the card 15, whereby the value of the card is eight cents. The outer face of the card 15, at one upper corner 110 and at one lower corner, is provided with an indication 8¢, as at 65, 66.

The card 16 has its outer face provided with conventional means to set up two spaced rows of superposed indications, each 115 in the design of a disk in perspective, provided with the term "One cent." The indications of one row are designated 67, 68 and 69, and the indications of the other row are designated 70, 71 and 72. The outer 120 face of the card 16, between the rows of indications, is provided with conventional means, as at 73, to constitute the representation of "One cent" and which is in the form of a disk in perspective, provided with the term "One cent." The outer face of the card 16, at one corner and at one lower corner, has the indication 7¢, as at 74, 75. The indications on the card 16 provide for a value of 125 seven cents.

The card 17 has its outer face provided with conventional means to constitute two rows of superposed "One cent" indications, and each of said indications is in the form 5 of a disk in perspective, provided with the term "One cent." Six indications are provided to form the card 17 of a value of six cents. The indications of one row are designated 76, 77 and 78, and the indications of 10 the other row at 79, 80 and 81. The outer face of the card 17, at one upper corner and at one lower corner, has the indication 6¢, as at 82, 83.

The card 18 has its outer face provided 15 with conventional means, as at 84, 85, 86 and 87, and each constituting the representation of "One cent" and each in the form of a disk in perspective, provided with the term "One cent." Four indications are provided 20 on the card 18 to give the card the value of four cents. The outer face of the card 18, at one upper corner and at one lower corner, is provided with the indications 4¢, as at 88, 89.

25 The card 19 has its outer face provided with conventional means, as at 90, 91 and 92, and each of which constitutes the representation of "One cent" and each is in the form 30 of a disk in perspective, provided with the term "One cent". Three indications are arranged on the outer face of the card 19 to provide for the value of three cents. The outer face of the card 19, at one upper corner and one lower corner, is provided with 35 the indication 3¢, as at 93 and 94.

The card 20 has upon its outer face, conventional means as at 95, 96 and each of 40 which constitutes the representation of "One cent" and each of the indications is in the form of a disk in perspective, provided with the term "One cent". Two indications are 45 provided to constitute the card 20 of the value of two cents. The outer face of the card 20, at one upper corner and at one lower corner, is formed with an indication 2¢, as at 97, 98. The indications 95, 96 provide the card 20 with a value of two cents.

The outer face of the card 21 has conventional means, as at 99 to constitute the 50 representation of "One cent" and which is in the form of a disk in perspective, having the term "One cent". At one upper corner and at one lower corner of the outer face of the card 21, the indication 1¢ is arranged, at 55 100, 101. The single indication 99 provides the card 21 of the value of one cent.

Each set of cards consists of a dollar card, 60 seventy-five cent card, fifty cent card, quarter card, ten cent card, five cent card, nine cent card, eight cent card, seven cent card, six cent card, four cent card, three cent card, two cent card and one cent card.

The card game apparatus in accordance 65 with this invention is designed for the playing of any number of card games, more espe-

cially the games of "Coins" and "Hi-lo-flip-flop".

The manner of playing the card game entitled "Coins" is as follows:

The game can be played by four or more 70 persons, but a less number will find it very interesting.

First the cards should be shuffled and one card dealt to each of the players, dealing to the left first and to the dealer last, and the 75 one who receives the highest card will be entitled to the deal. The cards are then shuffled again and the dealer then dealing to the left will deal out all the cards except four,

which will be placed face down, the deal to 80 be made one card at a time to each player. When the cards have been dealt and with the four cards placed face down, the player next to the dealer on the left should bid

from his hand of cards for the trump. 85 Trumps can be in any color or "no trump" in which event the highest denominational card played will take the trick regardless of color.

Say the first bid should be \$2.50 and the next one \$2.75, and the next \$3.00, and 90

the next \$3.25, and so on until the bidding has reached say \$4.00 or more when no one will raise it, then the highest bidder gets the four cards on the board. This is known as

the "Bank", from this bank the player will 95

select such cards as he wants and then discard an equal number of cards from his hand, leaving the player with the same number as held by the other players. If four or

six persons are playing the bank should consist of four cards, but if three only are playing 100 the bank should consist of five cards.

If as many as seven are playing it should consist of seven cards, so that each player should have the same number of cards in his 105 hand.

Now when the successful bidder has discarded, he has the right to play first, then the player on his left will play, and so on until all have played, and the one playing

the highest card of the same color lead, shall 110 take the trick. But it must be remembered that a certain color has been named trumps,

unless no trump is named, in which case the highest card played of the suit lead will take the trick, and if the party playing first 115

leads any certain color (or suit), every player must follow suit and play the same color if he has a card of that color in his hand, should the players not have a card of

the color lead, then he can play just any 120 card in his hand which he desires, or if

trumps are not lead and the player has a trump in his hand, he can trump it if he thinks the trick worth it. Therefore, a player must follow suit, and if he cannot do that

on account of not having a card of that suit 125 or color, then he can play any card he desires.

The game will continue in this manner until all the cards have been played, then each player will count up the value of 130

the cards he has taken in the play. Now in counting up the game, nothing but the cards bearing the denominations 5¢, 10¢, 25¢, 75¢ and \$1.00 are counted, that is, the 5 pennies are not counted or any card with pennies on it. It will be found that the whole pack of cards will therefore add but \$10.60. So when the adding of the counters is completed, have a sheet of paper handy on 10 which the names of the players are written, and place opposite their names the amount they have made, but if the bidder did not make the amount of his bid, he shall be declared set and will go in the hole the amount 15 of his bid, or the amount he bid shall be subtracted from what he has made on previous deals, provided such is the case. The cards are then shuffled again, and the deal and game continue as above described until some 20 one had made a total of \$20.00, when that game is over and the successful person declared the winner. The \$20.00 however can be changed to any amount the players may agree on, and thereby make the games 25 longer or shorter. It will develop however sometimes that two or more players will be about even and probably go out or make the \$20.00 during the same hand, in which case the successful bidder shall be the winner; 30 thus if one player has made a total of \$19.75 which is nearly out and the bidder should have only \$15.00 and bids \$5.00 or above and makes it, then he will be declared the winner, even though the player having \$19.75 to 35 his credit took a trick during the play which would put him out.

The card game entitled "Hi-lo-flip-flop" is played as follows:—

This game as indicated by the name is 40 something similar to the well known game of high, low, jack and the game, but vastly different in many respects, and much more interesting.

How played.

The cards dealt as in the game of "Coins" except the dealer will deal one at a time only six cards to each player. Then the one next on the left of the dealer shall bid from 50 his hand, and then the next and so on until the bidding has closed, remembering that only five points can be made, then after the bidding is closed, the successful bidder shall declare the trump in any color, or suit, he desires, then all players may discard from 55 their hands such cards as they desire and the dealer will deal to them an equal number to correspond with the number they have discarded, dealing to each person at one time 60 all the number of cards requested, but of course the player shall only hold but six cards, and should any player have more than six cards in his hand, it shall be declared a misdeal as to such player, or in fact as to all if 65 it is agreed to. The trump having been

declared, cards drawn, the playing begins by the bidder playing first and the one to his left playing next and so on, with the one next to the bidder playing last, then of course the high card or high trump wins 70 that trick etc., and if the bidder has made the amount of his bid, or more he shall be given credit for it, but if he has made less than his bid, he will be declared set and in the hole the amount of his bid, and all other 75 players will be given credit for what they have made. In counting up what has been made, remember that the highest card of the suit made trumps shall be one point, the lowest card of trumps will be one point and shall be given to the party playing it. The points "Flip" and "Flop" shall be given to the party catching them, as is the game. The game is counted as in "Coins" by counting dollars and cents, not counting cards 80 with pennies on them. Thus it will be found that the entire pack will add up only \$10.60, therefore, the person obtaining the most game, will be given that point. The amount of the game is eleven points, therefore, the 85 player who gets eleven points to his credit first is "out" and the game is over. However, just as in the game of "Coins" it may develop that two or more parties have gone out during the same hand, in which case the 90 bidder shall be declared the winner. This game is so interesting that when once played, it will be played again and again. This game requires much adding and subtracting 95 and the quick handling of figures, which is 100 very educating to both old and young.

Other games can be played with "Coin" cards, and in fact almost all the games played with playing cards can be played with a pack of these cards, by remembering that bidding etc., done by colors, and that each color represents a different suit.

What I claim is:—

1. A card game apparatus comprising a pack of cards formed of four differently colored sets, said sets of cards provided with corresponding indications, each card of each set provided with conventional means to constitute an indication to designate the financial value of the card, the financial value designation of each card of a set being different.

2. A card game apparatus comprising a pack of cards formed of four differently colored sets, each set consisting of fourteen cards, the sets of cards provided with corresponding indications, and each card of each set provided with conventional means to constitute the financial value designation of the card, the financial value designation of each card of a set being different.

3. A card game apparatus comprising a pack of cards formed of four differently colored sets, said sets provided with corresponding indications, each set consisting of 130

fourteen cards, the cards of each set having conventional means to constitute financial value designations to provide each set with a separate card of a value of one dollar, 5 seventy-five cents, half dollar, quarter dollar, dime, five cents, nine cents, eight cents, seven cents, six cents, four cents, three cents, two cents and one cent.

4. A card game apparatus comprising a 10 pack of cards formed of a plurality of sets, one of the cards of each set provided with conventional means to indicate the financial value thereof as of one dollar, each of the other cards of each set provided with conventional 15 means to indicate the financial value thereof as the fraction of a dollar,

each of the fractions of the dollar indications of each set being different.

5. A card game apparatus comprising a pack of cards formed of a plurality of sets, 20 each set consisting of fourteen cards, one of the cards of each set provided with conventional means to constitute a financial value indication of one dollar, each of the other cards of each set provided with conventional 25 means to constitute the financial value of the fraction of a dollar, the said fraction of the dollar indications being different from each other.

In testimony whereof, I affix my signature hereto.

JOHN L. HARRIS.
